UNITED STATES PATENT OFFICE.

MELVILLE A. HAWLEY AND WILLIAM L. RHOADS, OF ST. LOUIS, MISSOURI; SAID RHOADS ASSIGNOR TO SAID HAWLEY.

TELEGRAPHIC APPARATUS.

No. 806,891.

Specification of Letters Patent.

Patented Dec. 12, 1905.

Application filed April 3, 1905. Serial No. 253,476.

To all whom it may concern:

Be it known that we, MELVILLE A. HAWLEY and WILLIAM L. RHOADS, citizens of the United States, residing at St. Louis, in the State of Missouri, have invented a new and useful Improvement in Telegraphic Apparatus, of which the following is a specification.

Our invention relates to a combined telegraphic relay direct repeater and transmitter for automatically transferring telegraphic signals in either direction from one to the other of two normally closed circuits, and has for its object to simplify the repeating of signals directly from the relay-armatures without the use of intermediate transmitters, to obtain firmer signals and quicker response to breaks or interruptions from any point of signaling, and to increase the power at the relay of any given current.

20 The invention consists in features of novelty, as hereinafter described and claimed, reference being had to the accompanying drawings, forming part of this specification, whereon—

25 Figure 1 is a top plan view of our improved combination-relay direct repeater and transmitter, hereinafter referred to as "relay" for avoiding repetition of nomenclature, arranged in duplicate, with a system of wiring and line equipment therefor shown diagrammatically;

30 Fig. 2, a front elevation, to enlarged scale, of the relay, omitting the wiring; Fig. 3, a top plan thereof broken away; and Fig. 4, a vertical longitudinal section, partly in elevation, to exaggerated scale through the auxiliary magnet and adjacent armature forming parts of our invention, on line 4 4 in Fig. 1.

Like letters and numerals of reference denote like parts in all the figures.

40 A represents our improved relay at the terminal of the west main-line circuit, and A' a duplicate thereof at the terminal of the east main-line circuit.

The relays A A' respectively comprise the usual relay main-line magnets $a a'$ and an auxiliary magnet b , which are arranged in the order named side by side in central transverse horizontal alinement, the magnets $a a' b$ being successively located farther from the fulcrum of the main armature c , whereby the attractive power on the latter of each successive magnet from any given current is proportionately increased.

To the rear side of the main armature c ,

which in the present case is controlled by all the magnets $a a' b$, is fixed one end of a secondary armature d , which is preferably composed of a springy metal bar insulated from the main armature c at its attachment thereto by an interposed block e of insulating material, the free elastic end portion of the secondary armature d extending beyond the corresponding end of the main armature c and adapted to make contact with an adjustable contact-point f for repeating and transmitting signals along the desired line, while the free end of the main armature c is adapted to make contact with an adjustable contact-point g , which controls the auxiliary magnet b of the duplicate or east relay A'.

Behind the secondary armature d , at a suitable distance therefrom, is arranged an adjustable back-stop h for limiting the backward movement of the armatures c and d , which are held at a normal distance apart adjacent to the springy free end portion of the secondary armature d by an interposed block i of insulating material, which is affixed to the main armature c .

Behind the main armature c is arranged the usual adjustable retracting-spring k , and attached to the main-line magnets $a a'$ and auxiliary magnet b , respectively, is the spring and thumb-screw adjuster $l l'$.

1, 2, 3, 4, 5, 6, 7, and 8 are the usual binding-posts, to which on the under side of the base m (indicated by broken lines in Fig. 1) are connected the wiring from the magnet-coils, armatures, and contact-points above described, while from the said posts at the upper side of the base m pass the various wires, connecting the relays A A' together and to their coöperative switches, keys, local batteries, and main-line wires, as hereinafter more particularly referred to.

Under normal conditions the circuits of both the east and west main-line wires 9 9' are closed, the current passing along the east wire 9 to the binding-post 6 of the west relay A and thence to the secondary armature d and its contact-point f , thence by wire 10 to binding-post 5, and from the latter to switch 11 and binding-post 1 of the east relay A', thence to the main coils $a a'$ of the latter to the binding-post 2 thereof, and from the latter to the key 12 and main battery 13 to earth, and conversely in like manner as to the current passing along the west wire 9' to the binding-post

- 6 of the east relay A', and so on to the main battery 13' and earth, thereby creating magnetism in the cores of the main-line coils *a a'* of both relays A A', which attracts the armatures *c* and *d* and drawing them forward closes the contacts *f* and *g* of both relays A A' and in so doing shunts out the current from the auxiliary coils *b* of both relays A A', the local battery 14 of the west relay A being shunted by the main armature *c* of the east relay A' through its two contacts, one of which, the fulcrum of the armature *c*, is connected by wire 15 to the binding-post 8, thence to the connection of the wire 15 with the local wire 16, thence to switch 17 to one end of local battery 14 and through the latter back through the connection 18 to the binding-post 7 of the east relay A', and thence to the other adjustable local contact *g* thereof, the local battery 14' of the east relay A' being shunted out and the auxiliary coil *b* thereof controlled by the main armature *c* of the west relay A in like manner.
- With the circuits under normal conditions, as above described, there will be no current passing through either of the auxiliary coils *b*, the main armatures *c* of both relays A A' being held closed by the current passing through the main coils *a a'*.
- When desired to signal from the east along the main-line wire 9, the operator thereat opens and closes his key. Opening the circuit deprives the main coils *a a'* of the east relay A' of magnetism, which allows its armatures *c* and *d* to be drawn back by the retracting-spring *k*, which in turn opens the west main-line wire 9' through the wires before described, thereby depriving the main coils *a a'* of both relays A A' of their magnetism, but at the same time opens the shunt of the west local battery 14, and thereby allows the current to flow through the auxiliary coil *b* of the west relay A, which becomes magnetized and prevents the corresponding armatures *c d* from dropping back and breaking their contacts, thereby maintaining the continuity of the east main line 9, and conversely in like manner for maintaining the continuity of the west main line 9'.
- By the use of a secondary spring-armature *d*, fixed to and extending beyond the main

armature *c*, signals can be transmitted directly to the opposite line without an intermediate and separate transmitter, thereby simplifying the construction of the apparatus, reducing cost, obtaining firmer signals, and facilitating manipulation, adjustment, and repair. Also by the springiness of the secondary armature *d* we are able by proper adjustment to prevent a break back into the main line upon its being opened and closed, or, in other words, when the armatures *c* and *d* of either relay drop back the contact of the main armature at *g* is broken momentarily sooner than the contact of the secondary armature *d* with its contact *f*, thereby allowing the current from the local battery 14 or 14' to flow through either of the auxiliary magnets *b*, as the case may be, and so hold the armatures *c* and *d* of the opposite relay closed. Furthermore, by arranging the magnets successively farther from the fulcrum of the armature, as above described, the power of any given current is increased and a greater working margin of the apparatus obtained with a lighter and simpler form of armature.

It is to be here noted that the coils of the auxiliary magnets *b* are iron-clad with simple winding.

What we claim as our invention, and desire to secure by Letters Patent, is —

In telegraphic apparatus, the combination with a relay having the main-line magnets and armature for shunting the circuit of a local battery, of an auxiliary magnet, and a secondary springy armature fixed to, and insulated from the said main armature, the free end of the secondary armature being extended beyond the corresponding end of the main armature and adapted to make and break contact with an adjustable contact-point in the main-line circuit for directly repeating and transmitting signals into the opposite line, substantially as described.

In testimony whereof we have signed our names to this specification in the presence of two subscribing witnesses.

MELVILLE A. HAWLEY.
WILLIAM L. RHOADS.
